UNITED STATES PATENT OFFICE.

ALFRED HYMAN ANTHONY, OF COLCHESTER, ENGLAND.

VALVE MECHANISM FOR RECIPROCATING ENGINES.

1,336,711.

Specification of Letters Patent. Patented Apr. 13, 1920.

Application filed February 4, 1919. Serial No. 274,895.

To all whom it may concern:

Be it known that I, ALFRED HYMAN ANTHONY, a subject of the King of England, residing at Colchester, in the county of Essex, England, have invented certain new and useful Improvements in Valve Mechanism for Reciprocating Engines, of which the following is a specification.

This invention relates to valve-mechanism for reciprocating engines, viz., to slide valves of the type wherein the valve is connected to a plunger-and-barrel device, whereof the movable member is operated by the working-fluid admitted to the device through ports controlled by the working-piston, and the said member moves in a path parallel to that of the working-piston.

According to the present invention, a slide-valve of the type above defined is characterized by the barrel being the movable member and carrying the valve and having in its wall ports disposed on opposite sides of the plunger communicating through the wall of the working-cylinder with ports in the inner face of the latter and by the working-piston having pockets which connect the said ports to the fluid-supply and the exhaust in such manner that the barrel is reciprocated by fluid-pressure.

This invention further provides such a construction of slide-valve, characterized by the above-stated features, that the conduits connecting the ports in the barrel to the ports in the cylinder are all perpendicular to one and the same plane which also contains the longitudinal axis of the cylinder.

In the preferred construction according to this invention, a separate inlet-port and exhaust-port are provided for each end of the barrel and four pockets are provided in the piston, one for each of the said four ports. The object of this latter arrangement is to provide simplicity of construction and obviate the difficulties which are liable to arise from a construction in which a single cavity or pocket in the piston serves more than one purpose, or in which a single port for the barrel has to serve both as inlet and exhaust.

Other features of the invention will be described hereinafter with reference to the accompanying drawings.

One embodiment of the invention is illus-

trated by way of example in the accompanying drawings, wherein:

55

Figure 1 is a vertical longitudinal section showing one form of valve-mechanism according to the invention,

Fig. 2 is a vertical transverse section taken on the line 2—2 in Fig. 1,

60

Fig. 3 is a top plan view of the valve-chest and the ports therein as seen when the slide-valve has been removed,

65

Fig. 4 is a top plan view showing the working face of the working-piston, and

65

Fig. 5 is a bottom plan view showing the valve-face at the underside of the barrel-and-plunger device in the valve-chest.

70

Like reference letters designate like parts in all the views.

75

Referring to the drawings, the working-cylinder A containing the working-piston B is provided with the usual valve-chest C upon it wherein, as customary, is the seating C¹ for the slide-valve D¹ disposed upon the outer surface of the cylinder-wall. The slide-valve D¹ is integral with the barrel D which contains the plunger E of the aforesaid barrel-and-plunger device. The seating C¹ is pierced with nine ports c² to c¹⁰, 80 whereof three c², c³, c⁴ are on the center-line of the seating, which line is parallel to the axis of the cylinder, the center port c² of these three ports being the exhaust, as is usual, and the two extremes c³ and c⁴, 85 the inlet-ports for the corresponding ends of the cylinder. To one side of the inlet-port c⁴ are two smaller ports c⁵, c⁶ formed by holes drilled straight through the wall of the working-cylinder A at right-angles to the 90 working-face of the valve-seating. These two ports c⁵, c⁶ are in line with one another along a line at right-angles to the center-line above referred to of the seating, and are hereinafter referred to as the inner and 95 outer lateral inlet-ports respectively, since both are laterally placed on the seating and one is farther from the center-line than the other. On the opposite side of the center-line of the seating and approximately in line 100 with the said two lateral inlet-ports is what is herein described as a lateral exhaust-port c⁷ also formed by a hole drilled straight through the wall of the working-cylinder at right-angles to the face of the seating. At 105 the opposite end of the seating are three lat-

eral ports c^8 to c^{10} , two, c^8 , c^9 , to one side and one, c^{10} , to the other side of the center-line, arranged in relation to the other inlet-port c^3 for the working-cylinder in a corresponding manner, so that the two lateral inlet-ports c^5 , c^6 at one end are on the opposite side of the said center-line to the two lateral inlet-ports c^8 , c^9 at the other end.

The working-piston B is of such a length that neither end ever passes any of the openings in the cylinder-wall formed by the above-mentioned lateral ports. Unless, therefore, provision were made to the contrary, these ports would always be sealed at the inner surface of the working-cylinder by the cylindrical surface of the working-piston. Provision for opening the ports is made by means of pockets or recesses b^1 to b^4 in the cylindrical surface of the piston, there being four pockets in all, one b^1 to register simultaneously with the two lateral inlet-ports c^5 , c^6 at one end and bridge them, one, b^2 , for the corresponding ports c^8 , c^9 at the other end, and two more b^3 , b^4 whose general direction is inclined to the longitudinal axis of the piston and which serve each to put one of the lateral exhaust-ports c^7 , c^{10} into communication with a port c^{11} drilled through the cylinder-wall. This port c^{11} is virtually a continuation of the central exhaust-port c^2 and is drilled in continuation of it through the cylinder-wall parallel to the other ports.

The slide-valve D^1 , integral with the barrel of the plunger-and-barrel device, is formed on its outer, and otherwise cylindrical, periphery. On the face of the valve, in addition to slotted pockets d^1 , d^2 , d^3 to give the usual control of the inlet-ports c^3 , c^4 and the exhaust-port c^2 for the working-cylinder, there are four lateral slots d^5 to d^8 each so situated and of such a length that in all positions during the travel of the slide-valve it registers with one of the lateral ports in the seating. Thus, one such lateral slot d^5 registers with the inner lateral inlet-port c^5 , one slot d^6 with the corresponding lateral exhaust-port c^7 on the other side of the center-line, and the two slots d^7 , d^8 , at the other end are similarly disposed. The edge of the valve is furthermore cut away at diagonally-opposite points d^9 , d^{10} so that the two outer lateral inlet-ports c^6 , c^9 , which may be called admission ducts, are always open to the working-fluid in the valve-chest.

The four lateral slots d^5 to d^8 in the slide-valve communicate with the interior of the barrel by ducts drilled through the wall of the barrel so that a separate inlet- and exhaust-port are provided at each end of the barrel at opposite sides of the plunger, there being four ports in all through the wall of the barrel.

The plunger E for the barrel D is fixed,

being held by a rod F passing steamtight through a plug G in one end of the barrel and held in position by a head F¹ formed upon the rod and received in a slotted pocket c^{12} on an end-wall of the valve-chest, so formed that when the cover H of the chest is removed the barrel-and-plunger device can be lifted clear away without removing any further fastening. The barrel D is held down to keep the slide-valve D^1 upon its seating by coacting slidably with the cover H of the valve-chest C and in the latter there is fitted the spindle J of the customary starting-handle K.

It will be understood that the arrangement above described is such that as the piston B reaches one end of its stroke, one of its pockets b^1 or b^2 will bridge two lateral inlet-ports c^5 , c^6 or c^8 , c^9 , and the adjacent inclined pocket b^3 or b^4 will bridge the central exhaust-port c^2 and the lateral exhaust-port c^{10} or c^7 at the other end of the seating. In result steam (or other working-fluid) is exhausted from the barrel in the valve-chest on one side of the plunger and is admitted to the other, thus causing the barrel to travel and so carry the slide-valve across its seating to reverse the movement of the working piston.

What I claim as my invention and desire to secure by Letters Patent is:—

1. In a reciprocating engine the combination of a valve-chest carried on the working cylinder, a plunger-and-barrel device within the chest of which device the plunger is fixed and the barrel is movable in the chest in the direction of its own principal axis, a valve rigidly secured to the barrel within the chest, two admission ducts connecting opposed points in the interior of the chest with opposed points in the interior of the said cylinder, two inlet ducts connecting opposed ends of the interior of the barrel with opposed points in the interior of the cylinder, and two exhaust ducts connecting opposed ends of the interior of the barrel with opposed points in the interior of the cylinder, characterized by all of the said ducts having ports in the cylinder so situated as to be always masked by the piston in its movements and by the piston being formed with pockets so shaped and situated that in one position of the piston one of said admission ducts is connected with one of said inlet ducts, and one of said exhaust ducts is connected with the exhaust port of the working cylinder, and that in another position of the piston the other admission duct is connected with the other inlet duct and the other exhaust duct is connected with said exhaust port, while the pockets are inoperative at all other positions of the piston, substantially as described.

2. In a reciprocating engine the combina-

- tion of a valve-chest carried on the working cylinder, a plunger-and-barrel device within the chest of which device the plunger is fixed and the barrel is movable in the chest 5 in the direction of its own principal axis, a valve rigidly secured to the barrel within the chest, two admission ducts connecting opposed points in the interior of the chest with opposed points in the interior of the 10 said cylinder, two inlet ducts connecting opposed ends of the interior of the barrel with opposed points in the interior of the cylinder, and two exhaust ducts connecting opposed ends of the interior of the barrel 15 with opposed points in the interior of the cylinder, characterized by all of the said ducts having ports in the cylinder so situated as to be always masked by the piston in its movements and by the parts being so 20 situated and dimensioned that the ducts may be and are formed as straight drilled holes, and by the piston being formed with four pockets so shaped and situated that in one position of the piston one of said admission 25 ducts is connected by one pocket with one of said inlet ducts, and one of said exhaust ducts is connected by another pocket with the exhaust port of the working cylinder, and that in another position of the piston 30 the other admission duct is connected by a third pocket with the other inlet duct and the other exhaust duct is connected by the fourth pocket with said exhaust port, while the pockets are inoperative at all other 35 positions of the piston, substantially as described.
3. In a reciprocating engine the combination of a valve-chest carried on the working cylinder, a plunger-and-barrel device within 40 the chest of which device the plunger is fixed and the barrel is movable in the chest in the direction of its own principal axis, a valve rigidly secured to the barrel within the chest, two admission ducts connecting 45 opposed points in the interior of the chest with opposed points in the interior of the said cylinder, two inlet ducts connecting opposed ends of the interior of the barrel with opposed points in the interior of the cylinder, and two exhaust ducts connecting 50 opposed ends of the interior of the barrel with opposed points in the interior of the cylinder, characterized by all of the said ducts having ports in the cylinder so situated 55 as to be always masked by the piston in its movements and by the parts being so situated and dimensioned that the ducts may be and are formed as straight drilled holes extending at right angles to one and the 60 same plane, which plane also contains the longitudinal axis of the cylinder, and by the piston being formed with pockets so shaped and situated that in one position of the piston one of said admission ducts is connected with one of said inlet ducts, and one of said exhaust ducts is connected with the exhaust port of the working cylinder, and that in another position of the piston the other admission duct is connected with the other inlet duct and the other exhaust 65 duct is connected with said exhaust port, while the pockets are inoperative at all other positions of the piston, substantially as described.
4. In a reciprocating engine the combination of a valve-chest carried on the working cylinder, a plunger-and-barrel device within the chest of which device the plunger is fixed and the barrel is movable in the chest in the direction of its own principal axis, a valve rigidly secured to the barrel within the chest, four ducts each formed as a straight drilled hole two extending from one end of the barrel and the other two from the other end of the barrel to ports within 70 the cylinder, two other ducts also formed as straight drilled holes and each extending from the steam space of the valve-chest to within the cylinder and a piston within the cylinder formed with four pockets, two 80 pockets toward opposite ends of the cylinder, one situated and shaped to connect one of the ducts from one end of the barrel to one of the ducts leading from the steam space of the valve-chest, and the other similarly to connect one of the ducts from the other end of the barrel to a duct leading from the steam space of the valve-chest, and two pockets intermediate between the said 85 two, one to connect the remaining duct from 90 within the barrel to the exhaust port of the cylinder, and the other to connect the remaining duct from the other end of the barrel to the exhaust port of the cylinder, substantially as described. 95
5. In a reciprocating engine the combination of a valve-chest carried on the working cylinder, a plunger-and-barrel device within the chest of which device the plunger is fixed and the barrel is movable in the chest in the direction of its own principal axis, a valve rigidly secured to the barrel within the chest, four ducts traversing the barrel 100 wall and the valve-body and extending two from one end of the barrel and two from 105 the other end of the barrel to ports within the cylinder through the valve-body and its seating and opening at the working face of the valve into slots in that face whose length lies in the direction of travel of the valve, and each of which slots is of such length that in the travel of the valve the continuity 110 of communication by the said ducts between the interior of the barrel and the said ports within the cylinder is unbroken, admission ducts connecting the steam space within the valve-chest with ports within the cylinder, 115 and a piston formed with pockets so shaped 120
- 125

and situated that in one position of the piston one of said four ducts opening into one end of the barrel is put into communication with one of said admission ducts and another duct opening into the other end of the barrel is put into communication with the exhaust port of the working cylinder, while in another position of the piston one

of said four ducts opening into the latter end of the barrel is put into communication 10 with the other end of said admission ducts, and the fourth of said four ducts is put into communication with the said exhaust port, substantially as described.

In testimony whereof I affix my signature. 15
ALFRED HYMAN ANTHONY.
